J. P. Thomas

Attorney

UNITED STATES PATENT OFFICE.

CAMERON CLINTON ANDERSON AND FREDERICK ADAMS, OF WINDSOR, ONTARIO,
CANADA.

FUMIGATOR.

Application filed February 4, 1922. Serial No. 534,037.

To all whom it may concern:

Be it known that we, CAMERON CLINTON ANDERSON and FREDERICK ADAMS, subjects of Great Britain, residing at Windsor, county of Essex, Province of Ontario, Canada, have invented a certain new and useful Improvement in Fumigators, and declare the following to be a full, clear, and exact description of the same, such as will 10 enable others skilled in the art to which it pertains to make and use the same, reference being had to the accompanying drawings, which form a part of this specification.

Our invention relates to fumigators shown 15 in the accompanying drawings and more particularly described in the following specification and claim.

One of the objects of this invention is to provide a simple and inexpensive "knock-down" fumigator, for disinfection purposes, it being more especially designed for heating dry formaldehyde powder to a temperature at which formaldehyde gas is given off.

A further object of the invention is to 25 provide a container for housing dry formaldehyde, the cover for said container serving when removed from the latter as a holder or support for the heater or lamp, and also as the supporting base of the fumigator.

Another feature of the invention consists 30 in an annular wall,—mounted upon the cover when used as the base-plate of the fumigator—for supporting the formaldehyde container in spaced relation to a heater or lamp, housed within the annular wall.

Another feature of the invention consists 40 in constructing the annular wall of perforated sheet metal, or of wire fabric, to insure an even distribution of the air to the heater in order that perfect combustion and a steady flame, may result, thereby increasing the efficiency of the device.

A further object of this invention is to 45 reduce the fire hazard by protecting the gas from the naked flame of the lamp or heater, it being well known that the flame cannot pass through the screen to ignite the gas or nearby objects.

50 A further object in providing a supporting wall formed of wire fabric is to provide for maintaining the base at a relatively low temperature due to circulation of air and a further object is to permit the products of

combustion to pass off in an unobstructed 55 manner.

A further object is to provide for an uninterrupted view of the lamp or heater for the convenience and ready inspection of the 60 operator.

With the foregoing and other objects in view which will appear as the description proceeds the invention further resides in the combination and arrangement of parts 65 and in the details of construction herein-after described and claimed, it being understood that changes may be made in the precise embodiment of the invention herein disclosed without departing from the spirit of 70 the same.

In the drawings accompanying this specification:

Figure 1 is a side elevation of the device 75 showing the several parts in assembled relation.

Figure 2 is a vertical cross-sectional view 80 of the same.

Figure 3 is a vertical cross-sectional view 85 of the formaldehyde container and enclosing case used for protecting the dry powder, the cover serving also as the base-plate of the device when the parts are assembled as in the preceding views.

Figure 4 is a vertical cross-sectional view 90 of the heater or lamp with the cover in place, that shown being of the type commonly known as a solidified alcohol heater.

Referring now to the letters of reference 95 placed upon the drawings:

A, denotes a container for dry formaldehyde powder comprising a chamber A' fitted with a compression cover A² formed of sheet metal. The cover A² is also employed as the base of the fumigator when the respective parts are assembled, the cover having a central offset or depression A³, "struck-up" from the body of the metal to receive a lamp or heater. B, denotes the heater which in the present embodiment is of the type employed to contain "solidified" alcohol—but any other suitable lamp or heater may be employed. The heater is fitted with the usual compression cover B' of sheet metal and upon removing which the contents of the heater may be ignited. C, indicates an annular wall or collar, mounted upon the upstanding portion of the base or cover, A², for supporting the formaldehyde

container—sleeved in its upper end—in spaced relation to the heater. The supporting wall or collar C is preferably constructed of wire fabric as shown but it may 5 be made of sheet metal perforated for the passage of air and the products of combustion. It will also be apparent that the wall may be of flat sheet material with means for securing the ends together to form an 10 annular wall. Such a construction lends itself to a more compact form for boxing and shipment.

Having now indicated the several parts by reference letters the construction and operation of the device will be readily understood.

Dry formaldehyde being first lodged in the container the cover is removed and inverted as shown in Figure 2 to form the 20 base of the device. The annular woven-wire supporting collar or wall C, is now mounted upon the base and the heater B inserted in the central recess of the latter,—the cover of the heater is then removed and 25 its contents ignited. The chamber A containing the formaldehyde is then inserted in the upper end of the annular collar or

wall;—in spaced relation to the heater, whereupon the heat from the latter will release the formaldehyde gas, as may be readily understood.

Having thus described our invention what we claim is:

A device of the character described comprising a foraminous cylindrical body, a 35 disinfectant container fitting the upper end of the body and extending into the same and supported thereby, a heater of less diameter than the body, and a tapered cover 40 tightly fitting the container and having a marginal flange, and removable and reversible to form a base for the cylindrical body and to extend its tapered portion into the same, said cover having a central depression 45 of a size to receive the heater, and centering the same.

In testimony whereof, we sign this specification in the presence of two witnesses.

CAMERON CLINTON ANDERSON.
FREDERICK ADAMS.
